W. R. BANKSON

GRAVITY CONVEYER

Filed March 29, 1923

John Carrie Bankson, Inventor:
W R Bankson

UNITED STATES PATENT OFFICE.

WILLIAM R. BANKSON, OF ROSS TOWNSHIP, ALLEGHENY COUNTY, PENNSYLVANIA.

GRAVITY CONVEYER.

Application filed March 29, 1923. Serial No. 628,619.

To all whom it may concern:

Be it known that I, WILLIAM R. BANKSON, a citizen of the United States, residing in Ross Township, in the county of Allegheny and State of Pennsylvania, have invented a new and useful Gravity Conveyer, of which the following is a specification.

This invention appertains to conveyers and the primary object of the invention is to provide a novel means for transporting articles from one place to another in an expeditious manner with a minimum amount of expense.

A still further object of the invention is to provide a conveyer of the gravity type in which the carrier is adapted to move down an inclined way, the device being so constructed as to permit the same to be used for various purposes, either for light or heavy work.

A further prime object of the invention is to provide a gravity conveyer embodying a suspended track on which is mounted for movement thereover a wheeled carrier, and novel means for changing the inclination of the track, whereby the wheeled carrier can be made to move from one end of the track to the other at the will of the operator.

A further object of the invention is the provision of novel suspending means for the track and novel means for changing the inclination of the track, said suspending means being so constructed as to effectively support the track irrespective of the inclination thereof.

A still further object of the invention is to provide an improved gravity conveyer of the above character, which will be durable and efficient in use, one that will be simple and easy to manufacture, and one which can be placed upon the market at a small cost.

With these and other objects in view, the invention consists in the novel construction, arrangement and formation of parts, as will be hereinafter more specifically described, claimed and illustrated in the accompanying drawings, in which drawings:

Figure 1 is a side elevation of the improved gravity conveyer.

Figure 2 is a vertical transverse section through the same, illustrating the means of associating the wheeled carrier with the track, and

Figure 3 is a longitudinal section through the track showing the means for holding the car against movement, and

Figure 4 is a vertical transverse section through the complete apparatus illustrating the means for suspending the track.

Referring to the drawings in detail, wherein similar reference characters designate corresponding parts throughout the several views, the letter A generally indicates the improved gravity conveyer which embodies a track 10 upon which is mounted for movement thereover the carrier 11. The track 10 is of a novel configuration and embodies a body portion 12 including upstanding parallel marginal flanges 13, on which are adapted to travel the supporting wheels 14 of the carrier 11. Disposed at the longitudinal center of the body 12 is arranged an upstanding attaching flange 15 to which are pivotally connected as at 16 the supporting rods or hangers 17.

The carrier 11 includes a body 20 on which the articles to be transported are placed and this body 20 is supported by side frames 21 terminating in diverging arms 22. These diverging arms 22 carry the rollers 14.

Depending brackets 25 are secured to a suitable support such as a ceiling or the like 26 and the lower ends of these brackets 25 have pivotally connected thereto at their angles bell cranks 27. The bell cranks 27 are preferably arranged in two series one on each of the transverse center of the device and one series of the bell cranks are arranged in opposite relation to the other series, so that the short arms thereof extend in opposite directions. As clearly shown in Figure 1 of the drawing, the short arms of the bell cranks gradually increase in length toward the outermost bell cranks for a purpose, which will be hereinafter more fully described. The extreme upper ends of the supporting rods 17 are pivoted as at 28 to the terminals of the short arms of the bell cranks 27. The long arms of the bell cranks 27 are all connected together by means of a link 29 so as to permit synchronous movement thereof. The track 10 is so arranged as to swing in a vertical plane so as to change the angle thereof in relation to the horizontal and thus it is obvious that the ends thereof will have a greater

swinging movement than the center thereof, and this is compensated by the short arms of the bell cranks 27 decreasing in length toward the innermost pair of bell cranks, as heretofore stated.

The terminals of the track 10 are turned upwardly as at 30, so as to prevent the carrier 11 from slipping off the track when the same reaches the end of its traveling movement. It is also preferred to connect the longitudinally aligned axles of the wheels 14 together by means of a resilient band 18, which is adapted to engage a suitable retaining spring 19 secured to the body portion 12 of the track 10. This spring 19 engages the band 18 when the carrier reaches approximately the end of its movement and thereby brings about the gradual stopping of the carrier.

20 In order to change the inclination of the track a hanger 31 is arranged at each end of the row of hangers 25 and these hangers 31 have pivotally secured thereto at a point intermediate their ends the operating levers 32 and 33. The inner ends of the levers 32 and 33 are connected by means of a suitable cable or the like 34 with the terminals of the track 10. The levers 33 and 32 are connected beyond their pivots by means of a control rope or cable 35, which is trained about suitable guide pulleys 36 connected to the hangers 31.

In use of the improved device, when it is desired to move the carrier 11 from one 35 end of the track to the other, after the same has been loaded, it is merely necessary to pull down on one of the levers which will raise the corresponding end of the track and lower the opposite end of the track.

40 The changing of the inclination of the track 10 will move the supporting bell cranks 27 thereby still permitting the effective supporting of the track. The carrier 11 will now move down the track and thus transport the material carried thereby from one 45 end to the other. When it is desired to return the carrier to its first position it is merely necessary to move down the other lever which will change the inclination of 50 the track as in the first instance.

From the foregoing description, it can be seen that I have provided a gravity conveyer, which can be used for different purposes for effectively transporting material 55 from one point to another.

Changes in details may be made without departing from the spirit or the scope of this invention.

What I claim as new is:

1. A gravity conveyer comprising a longitudinally extending track, means for suspending the track from an overhead support, an operating lever arranged at each end of the track, means operatively connecting the levers to the track, means for operatively connecting the levers together for changing the inclination of the track, and a wheeled carrier arranged for movement over the track from one end thereof to the other according to the inclination of said track.

2. A gravity conveyer comprising a supporting track, a plurality of depending hangers, a plurality of oppositely disposed bell cranks pivoted at their angles to the hangers, the lowermost arms of the bell cranks decreasing in length toward the innermost hangers, means for connecting the bell cranks together for synchronous movement, means connecting the lower arms of the bell cranks to the track, means disposed at each end of the track for changing the inclination thereof, and a wheeled carrier mounted upon the track for movement thereover.

3. A gravity conveyer comprising a track including a flat supporting body, upstanding marginal flanges formed on the longitudinal edges of the body, a medial longitudinally extending flange formed on the body, a plurality of depending supporting hangers, bell cranks pivoted at their angles to the lower ends of the hangers, means connecting the long arms of the bell cranks together, means connecting the short arms of the bell cranks to the medial flange, a lever pivotally secured intermediate its ends at each end of the track, means connecting the inner end of each lever to the adjacent end of the track, means connecting the levers together, and a wheeled carrier including a supporting body, a frame, and wheels carried by the frame arranged to travel upon said marginal flanges.

4. In a gravity conveyer, a suspended track, means for changing the inclination of the track, a carrier mounted for movement over the track including a supporting body, side frames and rollers carried by the frames for engaging the track, a leaf spring carried by the track, and resilient bands connected with the carrier for engaging said spring to hold the carrier against movement on said track.

W. R. BANKSON.
